DESIGN FOR A CAR EMBLEM OR THE LIKE

Fred Knapke, Middle Village, N. Y.

Application September 10, 1941, Serial No. 103,269

Term of patent 3½ years

To all whom it may concern:

Be it known that I, Fred Knapke, a citizen of the United States, residing at Middle Village, Queens County, State of New York, have invented a new, original, and ornamental Design for a Car Emblem or the like, of which the following is a specification, reference being had to the accompanying drawing, forming part thereof.

The single figure in the drawing is a perspective view of a car emblem or the like showing my new design.

The opposite side of the car emblem or the like is substantially plain.

I claim:

The ornamental design for a car emblem or the like, substantially as shown and described.

FRED KNAPKE.
